CLAIM

The ornamental design for a container bracket or the like, as shown.

DESCRIPTION

FIG. 1 is a top perspective view of the container bracket or the like showing my design;
FIG. 2 is a side elevational view of the same;
FIG. 3 is a left end elevational view taken from FIG. 2;
FIG. 4 is a right side elevational view of the same; and
FIG. 5 is a bottom plan view of the same.
